UNITED STATES PATENT OFFICE.

CHAUNCEY K. ADAMS, OF MONTREAL, CANADA, ASSIGNOR TO THOMAS TRIMBLE, OF SAME PLACE.

BALLOT-PAPER OR VOTING-TICKET.

SPECIFICATION forming part of Letters Patent No. 448,403, dated March 17, 1891.

Application filed December 8, 1890. Serial No. 373,967. (No model.)

To all whom it may concern:

Be it known that I, CHAUNCEY KING ADAMS, of the city of Montreal, in the district of Montreal and Province of Quebec, Canada, have 5 invented a certain new and useful Improved Ballot-Paper or Voting-Ticket; and I do hereby declare that the following is a full, clear, and exact description of the same.

This invention has for its object to produce 10 a combined voting-paper and certificate of qualification of the voter in which the secrecy of the ballot shall be inviolably preserved and any chance of identification of any vote be absolutely prevented. I propose to effect this 15 by turning the sheet on which the names of candidates for election are printed over on a line midway between the top and a line of perforations extending across such sheet, the space below this perforated line being reserved for any certificate as to name, residence, &c., of the voter. The paper is then folded in the manner of a circular, being turned in, and is secured by a gummed corner, so as to prevent its being unfolded without 20 such unfolding being discovered. When the ticket is presented to the proper officer, the certificate is, before the paper is opened 25 by him, torn off without interfering with the body of the paper, thus entirely severing all 30 connection between the voter and his vote, and rendering it impossible to know the nature of the vote cast, leaving the certificate as a check on the ballot.

For full comprehension of the invention reference must be had to the annexed drawings, 35 forming part of this specification, in which—

Figure 1 is a view of the ballot-paper open; Fig. 2, a view of the same when first folded

down. Fig. 3 shows the folding in, and Fig. 4 front and rear views, of the ballot-paper in 40 shape to be deposited.

Like symbols indicate the same parts.

A is the ballot-paper proper, B the first line of fold, and C the line of perforations separating the ballot-paper from the certificate- 45 strip D, on which may be printed any data as to the voter's status or qualification.

It will be observed that it is entirely optional whether the certificate shall be printed simply on one face of the paper when folded 50 up or on both front and back. When folded up, the gummed corner E affords means by which the ballot-paper proper is completely closed.

The size of the ballot-paper A is immaterial, 55 as it is equally useful in cases where one of two candidates is to be chosen or a whole ticket voted upon.

What I claim is as follows:

1. In a ballot-paper or voting-ticket, the 60 combination of the sheet proper for candidates' names folded over, means for closing same, and a detachable visible certificate forming part of said sheet, all as and for the purposes set forth.

2. The combination, in a ballot-paper or voting-ticket, of the ballot-paper proper A, with fold at B, line of perforations C, certificate-strip D, and gummed corner E, all arranged and operated as herein set forth.

Montreal, November 3, 1890.

C. K. ADAMS.
